BLADE AND MOTOR HOUSING FOR A ROTARY LAWN MOWER

Clifford B. Stevens, Milwaukee, Wis., assignor to Outboard Marine Corporation, Waukegan, Ill., a corporation of Delaware

Filed June 22, 1959, Ser. No. 56,442

Term of patent 14 years

(Cl. D40—1)

FIG. 1 is a top perspective view from the right side and rear of a blade and motor housing for a rotary lawn mower showing my new design;

FIG. 2 is a perspective view taken from the left side and rear thereof;

FIG. 3 is an enlarged top plan view thereof;

FIG. 4 is an enlarged front elevational view thereof; and

FIG. 5 is an enlarged fragmentary cross-sectional view thereof taken on line 5—5 of FIG. 4.

I claim:
The ornamental design for a blade and motor housing for a rotary lawn mower, as shown.
